Primary Examiner — Andrew Kerr*Assistant Examiner* — Chariton Alexakis(74) *Attorney, Agent, or Firm* — Alexandra S. Anoff(57) **CLAIM**

The ornamental design for a packaging jar, as shown and described.

DESCRIPTION

FIG. 1 is a perspective view of a packaging jar showing our new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

In the drawings, the broken lines show portions of a packaging jar that form no part of the claimed design.
